UNITED STATES PATENT OFFICE.

ELLSWORTH A. HAWTHORNE, OF BRIDGEPORT, CONNECTICUT.

LAMP.

1,203,618.

Specification of Letters Patent.

Patented Nov. 7, 1916.

Application filed August 15, 1913. Serial No. 784,863.

To all whom it may concern:

Be it known that I, ELLSWORTH A. HAWTHORNE, a citizen of the United States, and a resident of Bridgeport, county of Fairfield, and State of Connecticut, have invented an Improvement in Lamps, of which the following description, in connection with the accompanying drawings, is a specification, like characters on the drawings representing like parts.

This invention relates to lamps, and more especially to electric lamps of the parabolic reflector type, and will be best understood by reference to the following specification, when taken in connection with the accompanying drawings of one specific embodiment thereof, while its scope will be more particularly pointed out in the appended claims.

20 In the drawings: Figure 1 is a central longitudinal plan section of an electric lamp embodying my invention; Fig. 2 is a sectional view on line 2—2 of Fig. 1; and Fig. 3 is a sectional view on line 3—3 of Fig. 1. 25 Referring to the drawings, and to the embodiment of my invention which I have selected for illustration, I have there shown an electric lamp having a casing 3, provided with a chamber 4, in which a reflector 5 is 30 mounted. This reflector may be of any other appropriate type, but herein is what is commonly known as a parabolic reflector, and in its center is mounted an electric bulb 6, provided with a shank or shell 7. This 35 shank is inserted in a connection 8 extending rearwardly through an aperture 9 formed in the casing 3, the outer end of the connection serving for the attachment of a cable 10. The mode of attachment of the 40 cable and the lamp to the connection 8 is old, and well known and understood by those skilled in the art.

The lamp and its connection 8 are mounted with relation to the reflector 5 in such 45 a manner as to be capable of adjustment for the purpose of focusing the lamp, and to that end, the reflector is provided with a rearwardly extending neck 11, which is internally screw-threaded to receive an external screw-thread 12 on the connection 8. The latter screw thread may be otherwise appropriately formed, but herein consists of a tubular member having a rolled thread. This member may be secured to the connection in any suitable manner, as by soldering

the same thereto. By simply rotating the lamp and its connection, it is caused to move axially and the focus may thereby be adjusted.

The lamp casing is herein provided with an inner screw-thread 13 and an outer screw-thread 14, the groove of one being preferably within the ridge of the other, and the thread being preferably formed by rolling or spinning the same. The reflector 5 is herein provided with a marginal flange 15, which may be threaded into the internal thread 13 in any appropriate manner, but herein the flange is provided with a plurality of lugs 16 forming an interrupted thread. The reflector is provided with a shoulder 17, which is firmly screwed against a shoulder 18 in the lamp casing 3, and the reflector is thus firmly held in position by simply screwing the same into place, and causing its shoulder to seat against the casing.

The front of the lamp casing is herein provided with a light-transmitting element 19, in the form of a glass mounted in a bezel or door 20, the latter being threaded onto the external threads 14 of the lamp casing in any appropriate manner. Herein the bezel is provided with a plurality of lugs 21, constituting an interrupted screw-thread similar to that already described. The lamp casing is provided with a laterally projecting flange 22, forming a shoulder against which a bead 23, formed on the bezel abuts, and insures a perfectly tight fit, thus excluding dust and moisture from the exterior of the casing.

In assembling the lamp, the reflector is first put in place, then the lamp connection is inserted, the electric bulb is attached to its connection after which the latter is adjusted to secure the proper focus, and finally the bezel is applied by forcing it axially upon the casing, the lugs of the bezel slipping over the thread of the casing until the last thread is reached, when the bezel is given a partial rotation and is screwed in place, thus closing the lamp and excluding dust and moisture, while preventing the adjustment of the lamp from being disturbed.

In connection with the hereinbefore described lamp, I may also provide a supplemental light 24, which is preferably so conditioned as to provide a light of materially lesser intensity than that given by the lamp 6.

This is frequently required at times when the blinding glare afforded by the large focused light 6 is not desired.

To render the light from the supplemental light 24 of materially lesser intensity, I have not only provided an electric bulb of considerably lower candle power than that of the bulb 6, but also located the bulb out of the lamp focus and herein well down in the lower portion of the parabolic reflector 5. This places the bulb well out of focus, giving a mild and widely diffused light, as contrasted with the concentrated search light beam from the lamp 6.

15 Any suitable socket fastening may be provided for the lamp 24, but herein substantially the same construction is selected as that provided for the lamp 6. When the lamp is equipped with the two lights as described, it will be understood that suitable connections are provided whereby either lamp may be cut out of circuit when the other lamp is in use.

While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made, without departing from the principles thereof.

Having thus described my invention, what I claim and desire to procure by Letters Patent is:—

40 1. In a lamp, the combination of a lamp

casing provided with inner and outer screw-threads, the groove of one being within the ridge of the other, a reflector provided with a thread engaging said inner thread, and a bezel or door provided with a thread engaging said outer thread. 45

2. In a lamp, the combination of a lamp casing provided with inner and outer screw-threads, a reflector provided with lugs engaging said inner thread, and a bezel or door 50 provided with lugs engaging said outer thread.

3. In a lamp, the combination of a lamp casing provided with inner and outer screw-threads, and having inner and outer shoulders, a reflector engaging said inner shoulder and provided with a thread engaging said inner thread, and a bezel or door engaging said outer shoulder and provided 55 with a thread engaging said outer thread. 60

4. In a lamp, the combination of a lamp casing the material thereof being distorted into inner and outer screw threads, a reflector provided with a thread engaging said inner thread and a bezel or door provided 65 with a thread engaging said outer thread.

5. In a lamp, the combination of a lamp casing the material thereof being distorted into inner and outer screw threads, a reflector provided with lugs engaging said inner thread and a bezel or door provided with 70 lugs engaging said outer thread.

In testimony whereof, I have signed my name to this specification, in the presence of two subscribing witnesses.

ELLSWORTH A. HAWTHORNE.
